HYDRAULIC HOIST

Karl Felleke, Gallon, Ohio

Application September 24, 1938, Serial No. 231,589

9 Claims. (Cl. 298—22)

This invention relates to devices in which a force, exerted by either one or more hydraulically operated jacks, is used to rotate a pivoted body, and where this force varies in magnitude owing to the changing resistance of the body to its rotation. A typical example of such a device is a hydraulic hoist for raising the dump body of a truck, for here the load imposed upon the hoist mechanism is much greater at the start of the dumping movement than at the finish. For this reason the advantages of my invention are demonstrated on a dump body equipped with a hoist of the direct push type.

One object of my invention is to provide means for applying the hydraulic force to the pivoted body with greater efficiency than heretofore on hoists of this particular type, thereby reducing the weight and cost of the required machinery to a minimum.

20 In a hoist of the direct push type the force exerted by the hydraulic jack is directly applied to the body, and the hoist mechanism is customarily mounted in the somewhat limited space between the body floor and the top of the truck frame. While this type of mounting greatly facilitates the installation of the hoist on the truck, it necessitates the placing of the jack at an unfavorable angle with reference to the body hinge and results in an inefficient application of 30 the hydraulic force. To remedy this defect is the main object of my invention.

A further object is to slow down the speed of rotation when the resistance of the pivoted body is greatest, thereby reducing the energy to be supplied to the hoist during the period of severest operating conditions.

Two embodiments of my invention are illustrated in the accompanying drawings, of which:

Fig. 1 is partly a side view and partly a longitudinal section through the hoist mechanism and the body showing the latter in its down or loading position.

Fig. 2 shows the same combination with the body raised to an intermediate position.

Fig. 3 shows the same combination with the body raised to its highest or dumping position.

Fig. 4 and Fig. 5 are diagrams of the forces exerted by the hoist mechanism.

Fig. 6 is a plan view of a hoist comprising a plurality of jacks arranged symmetrically with respect to the longitudinal plane of the truck. To show the arrangement clearly the body and various accessories have been omitted.

Fig. 7 is a side view of the hoist shown in Fig. 6 illustrating a combination in which the auxil-

iary jacks are larger in diameter than the main jacks.

In these drawings part 10 represents a supporting frame which contains the complete hoist mechanism and is mounted as an independent unit on top of the truck frame, but in some cases the supporting frame may be a part of the truck frame itself. A dump body 11 rests with its longitudinal sills 12 on the frame 10, being pivoted to the latter by means of the hinge pin 13, around which it can rotate until the dump position shown in Fig. 3 is attained. The body is equipped with the customary hinged tail gate 14 which opens when the body is tilted and permits the load to slide out.

The operating parts of my hoist mechanism consist of two cylinders, each comprising a cylinder barrel, closed at one end, and a sliding piston rod within that barrel, which protrudes at the other end. The piston rod will be referred to as 20 the pushing member, and the cylinder as the non-pushing or reaction member. The combination of cylinder and piston rod will be referred to as a hydraulic jack.

The main cylinder 15 is trunnioned at its lower 25 end by means of the pin 16 in the frame 10, and the piston rod 17 is trunnioned to the under-structure of the body 11 by means of the lift pin 18. The auxiliary cylinder 19 is resting with the cross bar 20, which is part of its closed end, loosely on the frame 10 in a predetermined position fixed by the link 21, the latter being pivoted on the cross bar 20 and with the pin 22 to the hoist frame 10. The piston rod 23 of the auxiliary cylinder is also trunnioned to the body, preferably at the lift pin 18 of the main cylinder piston rod.

In Figures 1, 2, 3 only one main and one auxiliary cylinder are shown. For dumping heavy loads a plurality of main and auxiliary cylinders 40 placed symmetrically to the longitudinal plane through the center of gravity of the body may be used. Such an arrangement is shown in Figures 6 and 7, where a pair of main and auxiliary cylinders is mounted on either side of the longitudinal plane A—A through the center of the truck.

Attached to the lower end of the main cylinder is the pump 24. This pump is operated by means of the shaft 25 from the truck engine or 50 any other available source of energy, and circulates the working fluid with which the system is filled.

The turning force R, exerted by the hoist mechanism, is the resultant of the forces created 55

by the two hydraulic cylinders 15 and 19; C_m being the force exerted by the main cylinder 15 and C_a that exerted by the auxiliary cylinder 19.

These forces are created by hydraulic pressure as follows:

The pump 24 draws the oil from the low pressure ends of the cylinders, i. e., the ends adjacent to the lift pin 18 through the pipes 26 and returns it under pressure through the pipes 27 to the high pressure ends of the cylinders, i. e., the ends adjacent to the supporting frame. This circulation of the working fluid is indicated by arrows in Fig. 1. The piston rods 17 and 23 move consequently, in their respective cylinders, away from the frame, pushing the lift pin 18 upwards and thus rotating the body on its hinge 13. Under pressure of the working fluid the piston rods move in their cylinders until they uncover the outlet ports 28 and 29 respectively, which permit the fluid to return through the pipes 26 to the pump. When these ports are uncovered the piston rods are held under pressure in their outward positions as long as the pump is working, and the flow of the working fluid under these conditions is indicated by arrows in Fig. 3. The movement of the piston rod is thus terminated by the same means in both cylinders.

As the auxiliary cylinder 19 is considerably shorter than the main cylinder 15, the former completes its stroke before the piston rod of the main cylinder has reached the end of its movement. The moment when the piston rod of the auxiliary cylinder has completed its stroke, i. e., when it has uncovered the outlet port 29, is shown in Fig. 2. From this point on, the auxiliary cylinder 19, while still under pressure, ceases to contribute a pushing force, is lifted off its seat on the supporting frame by its piston rod and is moved along with the body 11 until the latter, kept turning by the force C_m , reaches the position indicated in Fig. 3. During the interval indicated by Fig. 2 and Fig. 3, the lower end of the auxiliary cylinder is guided by the link 21. To accommodate the changing distance between the two cylinders the connecting pipes 26 and 27 are made of flexible material and are provided with sufficient slack in the down position to take care of the relative movement of the cylinder.

The lowering of the body to its loading position is accomplished in the conventional manner. A valve 30 operated through the rod 31 opens passages in the pump which permit the oil to flow in the opposite direction, i. e., back from the high pressure sides of the pistons to the low pressure sides. The weight of the body forces the oil to flow in this manner and the body settles gradually down to its loading position. During this lowering process the auxiliary cylinder is guided back to its starting position by the link 21. A ball check and by-pass (not shown) are usually provided in the pump to permit the holding of the body in any desired intermediate position. The particular pump and piping arrangement shown is only one possible arrangement, and not an essential part of the invention as my device may be associated with any other suitable pump and piping lay-out, which will perform the functions described.

Fig. 4 is a diagram which shows how much is gained by this novel cylinder arrangement over the conventional direct push type hoist. The main cylinder 15, without the auxiliary cylinder 19, typifies a direct push type hoist. If this cylinder by itself has to produce the tangential force R required to turn the body, it would have

to exert a force P as shown in the diagram. This force P has the desired tangential component R , but also an unwanted radial component S to the hinge pin 13, which merely increases the stresses in the parts and the friction losses. The same tangential force R , however, is produced with the two cylinders shown in Fig. 1 by the much smaller forces C_m and C_a and without added stresses and friction losses. The forces C_m and C_a have been superimposed on the forces P , R and S in Fig. 4, and a comparison shows that they are considerably smaller. As the pressures are alike in both cases it is obvious that the body can be turned by much smaller cylinders with my new hoist arrangement. While another shorter cylinder has been added as compared with the direct push type, there is a substantial net gain with my construction because weight and cost decrease approximately with the square of the cylinder diameters.

I have thus realized the main object of my invention, namely, to exert the hydraulic force with greater efficiency on a direct push type hoist, by adding to its cylinder a short stroke auxiliary cylinder at such an inclination towards it that the hydraulic force exerted by the latter creates a resultant with the force exerted by the main cylinder, which acts substantially in a tangential direction to the lift pin arc during the period of severest working conditions.

The second object of my invention, the slowing down of the turning movement during the period of severe load, is to some extent, automatically attained by the addition of any short stroke auxiliary cylinder regardless of its position; for a pump of a given size will take more time to fill two cylinders than one, thus slowing up the turning movement while the auxiliary cylinder is in action.

But a study of Fig. 5 shows that the degree of inclination of the two cylinders toward each other has an important bearing on the rate of slowing down. In Fig. 5 the forces C_m and C_a are shown as they are exerted by the two cylinders under the conditions shown in Fig. 1, that is, with the cylinders inclined toward each other at the angle α . Also shown are two forces C_m' and C_a' which give the same resultant R with the cylinders inclined at an angle α' . It is thus possible to obtain the same tangential resultant R with various inclinations of the auxiliary cylinder provided the forces exerted by the two cylinders are of the proper relative magnitude. While C_m and C_a are of the same magnitude, C_a' is considerably larger than C_m' . With equal oil pressure this means the auxiliary cylinder must also have a considerably larger diameter than the main cylinder to produce the force C_a' . A hoist with main and auxiliary cylinders of different diameters, producing the forces C_a' and C_m' , is shown in Figures 6 and 7.

It is evident that the piston rods do not move at the same speed in both cylinders, that rod moving faster which has the least deviation from the tangent on the arc B-B described by the lift pin. In the starting position the piston rod of the auxiliary cylinder moves faster and the pump consequently has to fill up more of the larger diameter cylinder at first. With the same amount of oil pumped per second this means a further slowing down of the turning movement when the cylinders are mounted with the included angle α' , as compared with the arrangement shown in Fig. 1.

Choosing such an inclination between the cylin-

ders that the largest auxiliary cylinder diameter possible under the circumstances is required, is therefore the only means for attaining the second object of my invention, namely, to reduce the 5 energy required to operate the hoist to a minimum.

Having thus described my invention, I claim:

1. The combination of a pivoted body with a hydraulically operated hoist mechanism mounted 10 as an independent unit on top of the truck frame, said hoist mechanism comprising a plurality of jacks which are trunnioned with their pushing members to said body and placed in radial arrangement relative to each other, said jacks being 15 located above the chassis frame to which the hoist mechanism is attached.

2. The combination of a pivoted body with a supporting frame and a hydraulically operated hoist mechanism comprising a plurality of jacks, 20 all of said jacks being trunnioned with their pushing members to said body, but not all jacks being trunnioned with their non-pushing members to the supporting frame.

3. The combination of a pivoted body with a hydraulically operated hoist mechanism comprising a plurality of radially arranged jacks trunnioned with their pushing members to said body, said jacks having different length reaction members and pushing members of different but 30 constant lengths.

4. The combination of a pivoted body with a hydraulically operated hoist mechanism comprising a main jack and an auxiliary jack, both trunnioned with their pushing members to the 35 body and mounted in radial arrangement relative to the trunnion pin; the main jack being trunnioned with its non-pushing member in the supporting frame, and the auxiliary jack being held in a predetermined contact position with the supporting frame by means connected with 40 said frame.

5. The combination of a pivoted body with a hydraulically operated hoist mechanism comprising a main jack and an auxiliary jack, both trunnioned with their pushing members to the 45 body; the main jack being trunnioned with its non-pushing member in the supporting frame, and the auxiliary jack resting with its non-

pushing member on said frame during the period of its activity, and rising up with the body after completing its stroke.

6. The combination of a pivoted body with a hydraulically operated hoist mechanism comprising a main jack and an auxiliary jack, both trunnioned with their pushing members to the body; the main jack being trunnioned with its non-pushing member in the supporting frame, and the auxiliary jack resting with its non-pushing member on said frame during the period of its activity, and rising with the body after completing its stroke, said auxiliary jack being guided during its movement by means connecting it with the supporting frame. 15

7. The combination of a pivoted body with a hydraulically operated hoist mechanism mounted as an independent unit on top of the truck frame, said hoist mechanism comprising a plurality of jacks which are trunnioned with their pushing members to said body and placed in radial arrangement relative to such other, and symmetrically relative to the longitudinal plane through the center of the truck, said jacks being located above the chassis frame to which the hoist mechanism is attached. 20

8. The combination of a pivoted body with a hydraulically operated hoist mechanism comprising a plurality of jacks of different lengths and diameters, said jacks being trunnioned to 30 the body at the lift pin and arranged radially relative to said lift pin so that the resultant force exerted by the jacks acts substantially at right angle to a line drawn through the lift pin and the body pivot. 35

9. A body hinged to a support, two hydraulically operated jacks of different lengths arranged to turn the body on its hinge, both jacks being trunnioned to the body and mounted in radial arrangement relative to the trunnion pin, the longer jack being also trunnioned to the support and thus effective during the whole turning period, the shorter jack merely contacting the support and free to rise with the body when its stroke is completed, thus being effective only during 40 the early part of the turning period. 45

KARL FEILCKE.
